UNITED STATES PATENT OFFICE.

ALBERT C. MELTON, OF SEDALIA, MISSOURI.

LAWN-MOWER.

No. 825,473.

Specification of Letters Patent.

Patented July 10, 1906.

Application filed November 22, 1905. Serial No. 288,623.

To all whom it may concern:

Be it known that I, ALBERT C. MELTON, a citizen of the United States, residing at Sedalia, in the county of Pettis and State of Missouri, have invented certain new and useful Improvements in Lawn-Mowers, of which the following is a specification.

My invention relates to lawn-mowers of the reciprocating-cutter-bar type, and has for its object the improvement of machines of that type, consisting in simplifying the construction thereof and providing an efficient and simple means for transmitting power to the cutter-bar.

15 The construction of my invention will be described in detail hereinafter, and illustrated in the accompanying drawings, in which—

Figure 1 is a front view of my improved lawn-mower; Fig. 2, a side view partly in section; Fig. 3, a detail view of the power-transmitting mechanism; Fig. 4, a detail view of one of the supporting-casters; Fig. 5, a detail view of one of the side plates.

In the drawings similar reference characters indicate corresponding parts throughout the several views.

My improved lawn-mower has a plate 1 at each side thereof, each of said plates having a stud-shaft 2 thereon, on which are journaled 30 the drive-wheels 3 and a pin 4, to which is secured the handle 5, 6 indicating other pins on said plates, against which the ends of the handle bear to enable the operator to lift the front of the machine. The cutter-bar 7 is of 35 the reciprocating type and is mounted near the front ends of plates 1.

8 indicates the drive-shaft, journaled in plates 1 and having spur gear-pinions 9 keyed to the ends thereof to mesh with a gear-face 10 on the inner side of the rim of drive-wheels 3. The middle of shaft 8 is formed with an obliquely-arranged crank 11, on which is journaled an arm 12, having a pin 13 slidably mounted therein with a ball 14.

45 15 indicates two blocks secured to cutter-bar 7 and having their abutting portions formed with hemispherical depressions 16 and comprising a socket in which the ball 14 is seated.

50 It will be understood that as the shaft 8 ro-

tates the free end of arm 12 is reciprocated, thus imparting a reciprocating motion to the cutter-bar 7.

17 indicates rollers journaled on short shafts 18, formed integral with serrated and slotted uprights 19 and adjustably secured to the front end of each plate 1 to regulate the height of the cutter-bar from the ground.

Having thus described my invention, what I claim is—

1. In a lawn-mower, a rotary shaft, an obliquely-arranged crank formed in said shaft, an arm journaled on said crank, a pin slidably mounted in said arm, a ball on the end of said pin, a reciprocating cutter-bar, and a 65 socket on said cutter-bar to receive said ball, substantially as shown and described.

2. In a lawn-mower, plates having stud-shafts thereon, the supporting-wheels journaled on said shafts, a shaft journaled in said plates having an oblique crank therein intermediate of its ends, operative connections between said shaft and the supporting-wheels, a reciprocating cutter-bar having a socket thereon, an arm journaled on said oblique crank, and a pin slidably mounted in said arm having a ball on its outer end mounted in the socket aforesaid, substantially as shown and described.

3. In a lawn-mower, plates having stud-shafts thereon, the supporting-wheels journaled on said shafts having internal gear-faces, a shaft journaled in said plates, gear-pinions keyed to the ends of said shaft and meshing with said internal gears, an oblique 85 crank formed in said shaft, an arm journaled on said crank, a pin slidably mounted in said arm and having a ball on its outer end, a reciprocating cutter-bar mounted between said plates, and a socket on said cutter-bar to receive the ball on the end of the pin, substantially as shown and described.

4. In a lawn-mower, plates having stud-shafts thereon, the supporting-wheels journaled on said shafts having internal gear-faces, a shaft journaled on said plates, gear-pinions keyed to the ends of said shaft and meshing with said internal gears, an oblique crank formed in said shaft, an arm journaled on said crank, a pin slidably mounted in said 95 100

2
arm, a ball on the end of said pin, a reciprocating cutter-bar mounted between said plates, a socket on said bar to receive said ball, pins on said plate, the handle secured to said pins, serrated uprights adjustably secured to the front ends of said plates, stud shafts projecting from said uprights, and

rollers journaled on said stud-shafts, substantially as shown and described.

A. C. MELTON.
